[57] CLAIM

The ornamental design for a stove top heating element, as shown and described.

DESCRIPTION

FIG. 1 is a top plan view of a stove top heating element showing my new design;

FIG. 2 is a side elevational view thereof;

FIG. 3 is a perspective view thereof;

FIG. 4 is a perspective view of the opposite side of FIG. 3; and,

FIG. 5 is a sectional view thereof, taken along lines 5—5 in FIG. 1.

The unilluminated bottom is flat and unornamented.
